METHOD AND APPARATUS FOR GENERATING ELECTRICITY.

1,128,229.

Specification of Letters Patent.

Patented Feb. 9, 1915.

Application filed November 10, 1911. Serial No. 639,540.

To all whom it may concern:

Be it known that I, DANIEL F. COMSTOCK, a citizen of the United States, residing at Brookline, in the county of Norfolk and State of Massachusetts, have invented certain new and useful Improvements in Methods and Apparatus for Generating Electricity; and I do hereby declare the following to be a full, clear, and exact description of the invention, such as will enable others skilled in the art to which it appertains to make and use the same.

The present invention has to do with a method and apparatus for the generation of electricity directly from heat by means of the ions or electrons.

One object of the present invention is to produce a method and an apparatus whereby electrical energy may be obtained directly from the heat energy of a combustible material.

Another object of the invention is to produce a method and an apparatus for guiding and controlling the ions or electrons.

With the above objects in view the present invention consists in the method and apparatus for generating electricity hereinabove described and particularly pointed out in the claims.

When a substance is heated to a sufficient temperature, charged ions or electrons are given off. Whether the ions are mostly positive or negative, depends on various conditions, except when the heated body is in a good vacuum, in which case the emitted ions are chiefly electrons. These electrons are negatively charged and their charge is large in proportion to their mass.

According to modern electrical theory, the electron is the ultimate unit of electricity—the fundamental entity in the science of electricity. According to this theory, an electric current can be considered as a stream of these electrons moving bodily through the minute spaces which exist in the substance of the conducting wire. Since the charge of the electron is negative, the electron stream runs through the wire in an opposite direction to what is ordinarily spoken of as the direction of the electric current. According to this highly probable modern theory, the state of affairs inside of metal is somewhat as follows: There are present atoms of the metal and electrons, the latter being very much smaller than the former. A certain number of these elec-

trons are not permanently attached to the atoms and are consequently called "free" electrons. The atoms contain permanently and in a state about which almost nothing is known at present, a certain amount of positive electricity, and when the number of electrons present is sufficient to just neutralize, as far as outside effects are concerned, this internal positive electricity, the body or single atom, as the case may be, is said to be uncharged. According to this view, therefore, a negatively charged body or single atom is one which contains more than the normal number of electrons, and a positively charged body or single atom is one which contains less than the normal number of electrons. The atoms and electrons within a body are in a state of ceaseless vibration which we call heat. What we know as the temperature of a body corresponds to the "violence" of this vibration. Although some of the electrons within a metal are free, no appreciable number can escape under ordinary conditions into the space surrounding the metal, because the attractions of the metal atoms for the electrons is too great. When, however, the violence of vibration, or more strictly speaking, the kinetic energy, is increased by raising the temperature of the body, a state is finally reached in which a considerable number of the free electrons at the surface of the metal have enough velocity to overcome the attraction of the metal and they thus "shoot" out into the surrounding space. The process of expelling electrons from heated metal or from bodies in general is, therefore, somewhat similar to evaporation of a liquid, and it can be shown that the process admits of thermo-dynamic treatment in a corresponding way.

It will be clear from the above that the driving off of electrons from a metal by means of high temperature involves the disappearance of heat, and the appearance of the energy of electric separation, that is, the electric energy corresponding to the negative charge removed from the metal. It is also clear that when electrons are absorbed by a metal, there is a corresponding appearance of heat at the expense of electric energy. The process of electron emission from a hot body and electron absorption in a cold body, therefore, is available for the transformation of heat energy into electric energy in accordance with the fundamental

principles of thermo-dynamics. The present invention involves the application of this idea.

When the negatively charged electrons flow out from a body the normal supply of electrons in the said body is impoverished and the body becomes positively charged. If the negative electrons are caught or absorbed by some other body, the normal number of electrons in it is increased so that it becomes negatively charged. When a body is heated to a sufficiently high temperature some of these negative electrons will be thrown off as above explained, some of the heat energy being utilized in overcoming the attraction of the body for the electrons. In this way the energy of the heat is directly transformed into the energy of electric separation, the electrical energy appearing simultaneously with the liberated electrons shot out from the heated body. Or, in other words, the heated body becomes positively charged because an electric current has been produced by the stream of electrons. If the stream of electrons emitted by the heated body impinges upon or is directed against another body, this second body becomes negatively charged and also heated. It is therefore necessary that some means be provided for cooling the second body or substance, as well as heating the first body or substance. Moreover, if the cool second body is in a direct line with the heated first body, the radiant heat from the first body will fall upon the second body, thus tending to a transfer of heat between the hot and cold bodies independently of the transfer of heat by the electrons, and to a consequent loss of efficiency. To prevent the radiant heat of the first body from falling upon the second body, it is desirable to screen the second body from the radiant heat of the first body. This necessitates moving the electrons in a curved path. To guide the electrons in a curved path advantage is taken of a magnetic field, the lines of force of which extend between the hot and cold bodies. The ratio of the electric charge to the mass of an electron (usually designated $\frac{e}{m}$) is so great that the forces of

inertia are often negligible in relation to the electro-magnetic force on the electron due to its motion through a moderately strong magnetic field. If an electron is projected across a magnetic field it is subjected to a force acting at right angles to its path of motion and at right angles to the lines of force of the magnetic field. This force will cause the rapidly moving electron to move in a circular path whenever an attempt is made to project it transversely to the direction of the lines of force of the magnetic field. If on the other hand the electron is projected in the direction of

the lines of force of the field there will be no electro-magnetic force due to the field acting on the electron since it does not cut the lines of magnetic force. The magnetic field, therefore, presents the remarkable quality of being a conductor in the direction of its lines of force for electrons and of preventing the electrons from moving great distances transversely to the lines of force unless their speed is very high. Therefore, a magnetic field having its lines of force extending between the electron emitting and the electron absorbing bodies will guide the electrons between them. The magnetic field offers no resistance to the movement of an electron in the direction of the lines of force so that the component of its velocity along the line of force is unopposed, but since motion across the lines of magnetic force causes the electron to move in a small circle, the resultant motion of a moving electron in a magnetic field will be a helical path along the lines of force. The cross-section of the helix will be very small if the magnetic field is strong and the electronic velocity small compared with the velocity of light. In a magnetic field of moderate density the diameter of the helix in which an electron travels is so minute that the electrons travel in practically straight lines along the lines of force and cannot escape from the magnetic field. In this manner the stream of electrons can be directed around corners or, in fact, in any path in which the lines of force of a magnetic field can be maintained.

In the foregoing general statement the electrons which have been considered, possess negative charges which are very great in comparison to their mass. However, the principle of the guiding of the negative electrons by means of a magnetic field may be applied to the separation of ions of different mass, because other ions, and particularly the positive ions, have a mass which is much greater in comparison with their electric charge, and therefore while the greatness of the charge in comparison to the mass of the electrons causes the inertia due to their mass to be negligible so that they cannot traverse a magnetic field but are guided along parallel to its lines of force, the mass of the ions which are of atomic size is large enough in comparison to the electric charge so that the inertia of these ions will carry them for some distance across a magnetic field. Therefore to separate the ions of atomic size, in particular positive ions, from those which have a relatively smaller mass, the ions may be projected across a magnetic field. The magnetic field will cause the paths of the ions of negligible mass to curl around in circles or helices and prevent the ions from passing across the field, while the greater mass of the ions of atomic size will carry them across the

field beyond a place at which the ions of negligible mass were arrested. Since a vacuum allows the passage of the electrons, it is preferable to maintain a vacuum between the hot and cold bodies of such degree of exhaustion as is most favorable to the passage of the electrons.

The present invention is illustrated in the drawing which shows, more or less diagrammatically, an elevation, taken partly in section, of an electric generator for producing an electric current directly from the heat of combustion.

Referring to the drawing, a vacuum chamber 2 is formed in a tube 4 which is bent at right angles at 6. The tube may be formed of any material which will not allow air to leak through it and which will withstand heat. The end walls of the vacuum chamber are formed by plates 8 and 10. The plate 8 is made of heat resisting material, and is preferably made either of a solid plate of a sufficiently electropositive metal or of a plate coated on its inner face with such a metal. The plate 8 is insulated from the walls of the tube 4 by means of an insulating bushing 12. This bushing is made of some heat resisting insulating material and forms an air-tight holder for the plate 8. The plate 8 is adapted to be heated to a red or white heat so that it will emit electrically charged ions or electrons. The plate 8 is illustrated as being heated by a gas flame 14, although a coal fire or any other means which would give sufficient heat might be used. A conductor 16 is brought through an insulated bushing 18 and is connected at 20 to the plate 8. The plate 10 is made of metal and is adapted to be kept cold by a stream of water. For this purpose the plate 10 is made hollow to provide a water chamber 22. The chamber 22 is lined with insulating material 24. Cold water is led into the water chamber 22 through an inlet pipe 26 and discharged through an outlet pipe 28. By means of the flame 14 and the water, a wide difference in temperature is maintained between the plates 8 and 10, and as is well known from the laws of thermodynamics, the greater the differences in temperature between the heat source and heat sink, the greater the efficiency of the apparatus from a thermodynamic standpoint. The plate 10 is insulated from the tube 4 by means of a collar 30 of insulating material which forms an air-tight joint between the tube 4 and the plate 10. A conductor 32 is connected at 34 to the plate 10. A pipe connection 36 runs to a vacuum pump by means of which the chamber 2 is exhausted to a high vacuum. The tube 10 is wrapped in a heat retaining packing 38 such as asbestos. Around the lower end of the tube in close proximity to the flame 14 is placed a ring of fire brick 40. A magnetic field is maintained in the

vacuum chamber by means of a magnetizing coil 46 wound around on the outside of the asbestos packing and adapted to conduct a direct current coming from some suitable source through the wires 47. The lines of magnetic force through the magnetizing coil 46 and the inclosed vacuum chamber 2 will extend between the plates 8 and 10, making a right angle turn at 6 where the tube and coil turn. Since the vacuum chamber turns at 6, the radiant heat from the hot plate 8 will not fall directly upon the cold plate 10 so that the useless transfer of heat between the plates by radiation is minimized. However, since the lines of magnetic force extend from the plate 8 to the plate 10, the negatively charged ions or electrons will move along the lines of force so that a stream of negatively charged ions or electrons is emitted from the hot plate 8, 85 is guided through the vacuum chamber 2, and impinges upon the cold plate 10. This stream of ions is in reality an electric current so that the plate 8 is maintained at a higher electric potential than at plate 10 90 and an electric current will flow out through the wire 16, through an external consumption circuit and back through the wire 32 to the cold plate 10. In this way the heat of the fire 14 is converted directly into electric 95 energy. Since the plate or wall 8 of the vacuum chamber may be directly heated to a high temperature by burning material, the operation of this electric generator is very simple. The heat of the burning material is directly applied to the hot body or substance and heats it to such a degree that it emits charged ions or electrons. The negatively charged ions or electrons are conducted to a cold body or substance and 100 the electric current formed by the stream of negatively charged ions or electrons is led off as a direct current through the conducting wires.

While the preferred embodiment of the present invention has been specifically illustrated and described, it is to be understood, however, that the present invention may be practised in methods and embodied in other forms of apparatus within the purview of 115 the invention and the scope of the following claims.

I claim—

1. The method of obtaining electric energy directly from the heat energy of combustible material which consists in causing the combustion of said material to directly raise the temperature of a substance to such a degree that it emits charged ions or electrons, and absorbing said ions or electrons by a substance at a lower temperature, whereby a difference of electrical potential is caused between the hot and the cold substance, substantially as described.
2. The method of obtaining electric en- 130

- 4
- ergy directly from the heat energy of combustible material which consists in heating a substance to such a degree that it emits charged ions or electrons, and guiding said charged ions or electrons by means of a magnetic field to a substance maintained at a lower temperature, whereby a difference of electrical potential is caused between the hot and cold substance, substantially as described.
- 5 3. The method of producing an electric current directly from heat which consists in heating a substance to such a degree that it emits charged ions or electrons, and absorbing said ions or electrons by a substance maintained at a lower temperature, substantially as described.
- 10 4. The method of obtaining electric energy directly from the heat energy of combustible material which consists in causing combustion of said material to raise directly the temperature of some substance to such a degree that it emits charged ions or electrons, and in causing said ions or electrons to traverse a vacuum and be absorbed by a substance maintained at a lower temperature whereby a difference of electrical potential is maintained between the hot and cold substances, substantially as described.
- 20 5. The method of producing electricity which consists in heating a substance to such a degree that it emits charged ions or electrons, and guiding said charged ions or electrons by means of a magnetic field to a second body maintained at a lower temperature than the first body, whereby the difference of electrical potential is maintained between the bodies, substantially as described.
- 25 6. An electric generator, having, in combination, a vacuum chamber having one wall adapted to be heated directly by a combustible material to such a degree that it emits charged ions or electrons and another wall adapted to be kept cool to absorb said charged ions or electrons, means for insulating said two walls from each other, and electrical connections leading from said walls, substantially as described.
- 30 7. An electric generator having, in combination, a vacuum chamber having one wall adapted to be kept hot and another wall adapted to be kept cold, means for maintaining a magnetic field having its lines of force extending between said two walls, means for insulating said walls from each other, and electrical connections leading from said walls, substantially as described.
- 35 8. An electric generator, having, in combination, a vacuum chamber having two walls insulated from each other, means for heating one wall directly by combustible material to such a degree that it emits charged ions or electrons, means for cooling the other wall, means for maintaining a magnetic field through the vacuum having its lines of force extending between said said walls, and electrical connections leading from said walls, substantially as described.
- 40 9. An electric generator having, in combination, a vacuum chamber having two walls insulated from each other and so situated that radiant heat cannot pass directly from one wall to the other, means for heating one wall directly from a combustible material to such a degree that it emits charged ions or electrons, means for maintaining the other wall at a lower temperature, means for maintaining a magnetic field through the vacuum having its lines of force extending between said walls, and electrical connections leading from said walls, substantially as described.
- 45 10. An electric generator having, in combination, a vacuum chamber having one wall adapted to be heated to such a degree that it emits charged ions or electrons and having another wall maintained at a lower temperature, said colder wall being so situated that it will not directly receive radiant heat from the warmer wall, means for maintaining a magnetic field having its lines of force extending between said walls, means for insulating said walls from each other, and electrical connections leading from said walls, substantially as described.
- 50 11. An electric generator having, in combination, a vacuum chamber having two walls insulated from each other, means for heating one wall directly by a combustible material to such a temperature that it emits charged ions or electrons, means for maintaining the other wall at a lower temperature, means for insulating said walls from each other, and electrical connections leading from said walls, substantially as described.
- 55 12. An electric generator having, in combination, a substance adapted to be heated to such a degree that it emits charged ions or electrons, a second substance maintained at a lower temperature than said first substance and arranged to receive and absorb the charged ions or electrons emitted from the first substance, means for insulating said substances from each other, and means for conducting away the electric current caused by the emission and absorption of the charged ions or electrons, substantially as described.
- 60 13. An electric generator having, in combination, a substance adapted to be heated to such a degree that it emits charged ions or electrons, a second substance adapted to be maintained at a lower temperature than the first substance and arranged to receive and absorb the charged ions or electrons emitted from the first substance, means for maintaining a magnetic field having its lines of force extending between said sub-

stances, means for insulating said substances from each other, and means for conducting away the electric current caused by the emission and absorption of the charged ions or electrons, substantially as described.

14. An electric generator having, in combination, a vacuum chamber having two walls insulated from each other and screened from each other to prevent direct interchange of radiant heat, means for heating one wall to such a degree that it emits charged ions or electrons, and means for cooling the other wall, substantially as described.

15. An electric generator having, in combination, a body adapted to be heated to such a degree that it emits charged ions or electrons, a body adapted to be maintained at a lower temperature than the first body, and means for screening the second body from the radiant heat of the first body, substantially as described.

16. The method of conveying ionic electric charges from one body to another which consists in heating the first body to such a degree that it emits charged ions or electrons, guiding the charged ions or electrons by means of a magnetic field to the second body, said second body being maintained at a lower temperature than the first body, substantially as described.

17. The method of conveying ionic electric charges from one body to another which consists in heating the first body to such a degree that it emits charged ions or electrons, and conducting said charged ions or

electrons through a vacuum by means of a magnetic field the lines of force of which extend between the two bodies, the second body being maintained at a lower temperature than the first body, substantially as described.

18. The method of separating ions or electrons of large mass from those of small mass which consists in the use of a magnetic field of such strength that the ions or electrons of large mass are allowed to pass across the field while the ions or electrons of small mass are guided in the direction of the lines of force of said field, substantially as described.

19. The method of separating ions or electrons of large mass from those of small mass which consists in the use of a magnetic field of such strength that the ions or electrons of large mass are allowed to pass across the field while the ions or electrons of small mass are prevented from passing, substantially as described.

20. An electric generator having, in combination, a vacuum chamber having two walls insulated from each other and means for reducing the interchange of radiant heat therebetween, means for heating one wall to such a degree that it emits charged ions or electrons, and means for cooling the other wall, substantially as described.
